CAN OPENER HOUSING OR THE LIKE

Walter W. Edlund, Burlington, Vt., assignor to Edlund Company, Inc., Burlington, Vt., a corporation of Vermont

Filed Oct. 23, 1958, Ser. No. 53,102

Term of patent 7 years

(Cl. D22—2)

FIG. 1.

FIG. 5.

FIG. 2.

FIG. 4.

FIG. 3.

The portions of the can opener shown in broken lines on the drawing are for illustrative purposes only.

I claim:

The ornamental design for a can opener housing or the like, as shown and described.
